[57] CLAIM

The ornamental design for a cutting board for a double sink,
as shown and described.

DESCRIPTION

FIG. 1 is a perspective view of a cutting board for a double sink showing my new design;

FIG. 2 is a top plan view of FIG. 1;

FIG. 3 is a bottom plan view of FIG. 1;

FIG. 4 is a right side elevational view of FIG. 1; left side
elevational view being a mirror image; and,

FIG. 5 is a front elevational view of FIG. 1; the rear
elevational view being a mirror image.

The broken line showing of a double sink in FIG. 1 is for
illustrative purposes only and forms no part of the claimed
design.
